UNITED STATES PATENT OFFICE.

GUY L. WOODJARD, OF SAN DIEGO, CALIFORNIA.

SPRING-OILER.

1,178,770.

Specification of Letters Patent. Patented Apr. 11, 1916.

Application filed January 5, 1916. Serial No. 70,387.

To all whom it may concern:

Be it known that I, GUY L. WOODJARD, a citizen of the United States, residing at San Diego, in the county of San Diego and State of California, have invented certain new and useful Improvements in Spring-Oilers, of which the following is a specification.

My invention relates to a device for lubricating springs for vehicles and the like and the objects of my invention are, first, to provide a device of this class which will retain the oil and allow it to seep gradually between the leaves of the spring, second, to provide a device of this class which is noiseless and to which oil is easily applied, third, to provide a device of this class which is applicable to the different kinds and varieties of springs, it being made in different widths for different width springs, and fourth to provide a device of this class which is simple and economical of construction, durable, easily installed and will not readily get out of order.

With these and other objects in view as will appear hereinafter, my invention consists of certain novel features of construction, combination and arrangement of parts as will be hereinafter described in detail and particularly set forth in the appended claims, reference being had to the accompanying drawings and to the characters of reference thereon which form a part of this specification, in which:

Figure 1, is a longitudinal sectional view of my device shown mounted on the spring which is shown in dotted lines and showing by dotted lines the insertion of the oil can spout for filling the device with oil; Fig. 2, is a longitudinal sectional view of the device itself; Fig. 3, is a perspective view of said device and Fig. 4 is a bottom view of the same.

Similar characters of reference refer to similar parts throughout the several views.

The casing 1, pad 2 and oil hole cover 3 constitute the principal parts of my oiler.

The casing 1 consists of a rectangularly shaped piece, preferably metallic, provided with downwardly extending right angled flanges 1^a which are provided with inwardly extended portions 1^b along their lower edges. These portions 1^b are adapted to fit into the usual slight grooves between the two upper spring leaves and hold the device in posi-

tion on the upper spring leaf. The main portion is provided at one end with an extended portion 1^c which is bent back against itself for the purpose of adding to the compression of the pad and making a tight fit 60 of the pad against the upper surface of the spring to prevent the oil from seeping out between the upper surface of the spring and said pad. However it is obvious a separate piece may be inserted in the place of this portion 1^c to perform the same function. This main portion is also provided with an oil hole 1^d adapted for the insertion of the oil and this hole is covered with a cover 3 which is rigidly secured to the main portion 65 1 at one end in the middle thereof and its opposite end is bent upwardly at 3^a to facilitate the insertion of the oil can spout to the hole 1^d. This cover is for the purpose of preventing dirt and dust from entering the 70 hole and mixing with the oil. Mounted on the lower surface of the main portion 1 and between the two flanges 1^a is a pad, preferably of felt provided with a central hole 2^a of suitable size to contain a sufficient quantity of oil. This pad 2 is sufficiently compressed to make a tight fit against the upper surface of the upper spring leaf but will allow the oil to seep out gradually along 75 the sides and run down between the leaves 80 of the spring when the springs are in operation.

Though I have shown and described a particular construction, combination and arrangement of parts, I do not wish to be 90 limited to this particular construction, combination and arrangement but desire to include in the purview of my invention the construction, combination and arrangement, substantially as set forth in the appended 95 claims.

It is obvious that with this construction, there is provided an oiler for spring which will allow the oil to seep down between the leaves of the spring when said springs are 100 in operation: that the pad provides combined means for retaining the oil, allowing its seepage, for preventing noise and providing a tight fit on the spring leaf: that the cover over the oil hole therein is so 105 shaped that the oil can spout may be readily inserted and removed: that the device is very simple and economical of construction, durable and easily installed.

Having thus described my invention, what 110

I claim as new and desire to secure by Letters Patent, is:

1. In a spring oiler, the combination of a casing provided with side members adapted to fit over the upper leaf of the spring and a resilient pad provided with a central hole for an oil retainer.
2. In a spring oiler, the combination of a casing provided with side members adapted to fit over the upper leaf of the spring and with an oil hole therein, a resilient pad provided with a central hole for an oil retainer and a cover for the oil hole in said casing.
3. In a device of the class described, the combination of a casing adapted to fit over

the upper leaf of a spring provided with an oil hole therein, a felt pad provided with a central hole therein mounted between the top portion of said casing and the upper surface of said spring and means for covering the oil hole in said casing. 20

4. In a device of the class described, a metal casing provided with an oil hole and a reservoir, and adapted to clamp securely over the upper leaf of a spring by reason of 25 the inherent spring of the metal.

In testimony whereof, I have hereunto set my hand at San Diego, California this 31st day of December 1915.

GUY L. WOODJARD.
